UNITED STATES PATENT OFFICE.

CHARLES J. KLEIN, OF MILWAUKEE, WISCONSIN, ASSIGNOR TO THE CUTLER-HAMMER M'F'G CO., OF MILWAUKEE, WISCONSIN, A CORPORATION OF WISCONSIN.

ELECTRIC SWITCH.

1,198,038.

Specification of Letters Patent. Patented Sept. 12, 1916.

Application filed February 24, 1914. Serial No. 820,530.

To all whom it may concern:

Be it known that I, CHARLES J. KLEIN, a citizen of the United States, residing at Milwaukee, in the county of Milwaukee and 5 State of Wisconsin, have invented new and useful Improvements in Electric Switches, of which the following is a full, clear, concise, and exact description, reference being had to the accompanying drawing, forming 10 a part of this specification.

This invention relates to electric switches.

One of the objects of the invention is to provide a compact and sturdy snap switch mechanism capable of efficient use in various 15 forms of switch devices.

In order to more clearly disclose my invention I have illustrated a preferred embodiment thereof in the accompanying drawing. It is to be understood, however, that 20 the mechanism shown is susceptible of modification and capable of use in devices other than that represented.

In the drawing, Figure 1 is a plan view of a switch mechanism; Fig. 2 is a sectional view on the line 2—2 of Fig. 1; Fig. 3 is a 25 top view of the switch mechanism incorporated in a surface switch device, the cover of the latter being removed; and, Fig. 4 is a sectional view on the line 4—4 of Fig. 3.

30 The switch mechanism illustrated comprises, in general, a reciprocating operating member, 1, a reciprocating contact 2, and an energy storing connection between the two, including a spring 3, for effecting a snap 35 movement of the contact upon actuation of the operating member.

Referring more specifically to the drawing, the operating member comprises a stamped plate 4 having push button extremities 40 and slidably mounted on a stationary U-shaped frame 5. The upright ends of this frame are provided with alined recesses for receiving and guiding the operating member. The contact member 1 also preferably 45 comprises a stamped plate having a body-portion 2 superposed on the operating plate and held in position thereon. An upright spindle 8 is carried by a lateral extension 9 of the frame and itself carries the coil spring 3, which latter has straightened radial extremities 10 and 11 projecting across the upper surface of the contact and operating plates. The extremities of the spring are biased apart and restrained against separa-

tion by engagement with lugs 12 and 13 on 55 the contact plate 2 and corresponding lugs 14 and 15 on the operating member.

The relation of the parts thus far described is such that movement of the operating member would tend, through the medium of the coil spring, to move the contact member in the same direction. Locking means is provided to restrain movement of the contact member until after the spring has been tensioned. This means comprises a 60 plate 16 reciprocable in a direction at right angles to the direction of movement of the operating member and having a shoulder 17 adapted to enter one of two notches 18 in the contact member to lock the latter against 65 movement. The locking plate is guided in movement and held in position by lugs 19 on the stationary frame and is biased inwardly by a short contraction spring 20 secured to the spindle 8. The operating plate 70 4 is provided with a concave recess on its outer edge affording inclined cam faces 21 adapted to engage the plate 16 as the operating member is reciprocated to move the same away from the contact and out of engagement with the sides of the notch therein. The cam faces 21 of the operating plate are 75 so spaced that the operating member is free to move substantially throughout its entire range of reciprocation prior to engagement 80 of either cam face with the plate 16.

Referring to Figs. 3 and 4, the switch mechanism is illustrated as applied to a surface switch device. In this embodiment a substantially rectangular insulating base 22 85 is provided with a recess 23 having the switch mechanism centrally mounted therein by suitable means, such as a screw extension 24, of the spindle 8. At one end of the base are located a pair of stationary contacts 90 provided with contact surfaces 25 lying in a plane for engagement with the bridging end 6 of the switch contact and having binding posts 26 for connection with line wires entering the base through adjacent apertures 95 27. The opposite walls of the base are provided with recesses to accommodate the push-buttons of the switch operating member.

Assuming the switch to be in the "off" 105 position shown in Fig. 3, pressure on the right push button effects the following operation of the mechanism: The lug 15 of the

operating member presses against and carries the extremity 11 of the coil spring 3 toward the left and accordingly tensions the spring since its opposite extremity 10 is held 5 against movement by engagement with the contact lug 12. The contact in turn is restrained against movement by the shoulder of the locking plate 16 projecting into the notch 18. As movement of the operating 10 member is continued, however, the right cam face 21 of the latter engages, at approximately the extreme movement of the operating plate, with the locking member 16 and forces the latter to freed position. The tension 15 of the spring is thus suddenly released and the contact member is rapidly thrown to the left by means of the spring arm 10. Circuit between the stationary contacts on the base is thereupon closed with a snap 20 action. In this position the sliding plate 16 is again biased inwardly by the spring 20 and adjusts the parts so that the plate is projected into the other notch 18 of the contact member. Opposite reciprocation of the 25 operating member reverses the co-action between the parts in a manner similar to that described and effects at its limit of reciprocation a snap movement of the contact to "off" position.

30 Movement of the operating member is limited in any suitable manner, for example, by means of engagement between the lugs 14 and 15 of the operating member with the end walls of the stationary frame 5. It is to be noted that reciprocation of the operating 35 member is limited at substantially the moment the contact member is thrown to its opposite position, and that if pressure is removed from the operating member at any 40 time prior to the snap actuation of the contact the spring acts to return the operating member to its former extreme position. Movement of the contact member is limited by engagement between its shouldered extremities and the outer ends of the frame 45 uprights.

What I claim as new and desire to secure by Letters Patent is:

1. In an electric switch, in combination, a 50 supporting frame, a reciprocable operating member mounted thereon and guided thereby, a reciprocable contact member, a pair of spaced lugs on each of said members, a spindle mounted on said frame and offset from 55 said members, a coil spring on said spindle having extremities biased apart and restrained between said lugs, a reciprocable member biased to engage and lock said contact member in each extreme position of the 60 latter, and a concave cam carried by said operating member and adapted to engage said locking member for reciprocating the latter out of engagement with said contact member.

65 2. In an electric switch, in combination, a

frame, a reciprocable operating member thereon, a reciprocable contact member aligned with said operating member, a pair of spaced lugs on each of said members, a coil spring having extremities biased apart and restrained between said lugs, a reciprocable locking member biased to engage said contact member for locking the latter in each extreme position, and a concave cam movable with said operating member and adapted to engage and reciprocate said locking member as said operating member approaches either extreme position. 70

3. In an electric switch, in combination, a reciprocable operating member, a reciprocable contact member and an energy storing connection therebetween comprising a pair of spaced lugs on each of said members, a relatively stationary coil spring having extremities biased apart and restrained between said lugs of said two members, a locking member for retaining said contact member in each extreme position and means carried by said operating member and adapted to move said locking member to release said contact member as said operating member approaches either extreme position. 75

4. In an electric switch, in combination, a reciprocable operating member, a reciprocable contact member and an energy storing connection therebetween comprising a pair of spaced lugs on each of said members, a relatively stationary coil spring having extremities biased apart and restrained between said lugs of said two members, and means for releasably restraining said contact member against movement. 80

5. In an electric switch, in combination, a reciprocally acting operating member, a reciprocally acting contact member, an energy storing connection therebetween, an integral stamped metal frame for supporting said parts comprising a base and upstanding lugs spaced to support said reciprocally acting members for movement therebetween and constituting stops to limit movement of both said members in either direction. 85

6. In an electric switch, in combination, a reciprocally acting operating member, a reciprocally acting contact member, an energy storing connection therebetween including a reciprocally acting latch, a stamped metal frame for supporting said members comprising a base and integral upstanding lugs spaced to support all of said reciprocally 90 acting members for movement therebetween and certain of said lugs constituting stops to limit movement of said operating member and said contact member in either direction. 95

7. In an electric switch, in combination, a reciprocable operating member, a relatively movable contact member, an energy storing operative connection between said members comprising lugs on said members and a coil spring having extremities biased toward said 100 105 110 115 120 125 130

lugs, a reciprocable locking member to hold said contact member against movement during a predetermined initial movement of said operating member, a coil spring biasing 5 said locking member toward said contact member, and a concave cam carried by said operating member and having active faces to engage and reciprocate said locking member to its releasing position after said first-men-

tioned spring has been tensioned by relative 10 movement of said lugs.

In witness whereof, I have hereunto subscribed my name in the presence of two witnesses.

CHARLES J. KLEIN.
